UNITED STATES PATENT OFFICE.

THOMAS G. HAWKES, OF CORNING, NEW YORK.

DESIGN FOR THE ORNAMENTATION OF GLASSWARE.

SPECIFICATION forming part of Design No. 19,114, dated May 28, 1889.

Application filed April 29, 1889. Serial No. 309,074. Term of patent 14 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification.

In order that my invention may be fully understood, I will proceed to describe the same with reference to the accompanying drawings, in which—

Figure I is a bottom plan view of my design as applied to a glass bowl. Fig. II is a cross-section thereof. Fig. III is a bottom plan view of a dish having my design as an ornamentation. Fig. IV is a perspective view of a stem-glass having my design applied to the cup thereof.

My design is for the ornamentation of glass and other ware, such as bowls, decanters, and stem and other glassware.

My design extends from the center star to the outer edge of the article, and the leading features thereof are an intermediate circular or encircling line and pairs of crossed curved lines extending in opposite directions from the center star toward the edge, crossed at their inner ends and crossing or meeting other pairs of crossed curved lines at their outer ends.

1 is a circular or encircling line intermedi-

ate of the star and the outer edge of the bowl.

2 2^a are a pair of curved lines crossed at their inner ends and extending from the star outwardly in one direction beyond the circular line.

3 3^a are a pair of curved lines crossed at their inner ends and extending from the star outwardly in the opposite direction beyond the circular or encircling line and crossing or meeting the first-named pairs of curved lines. The pairs of crossed curved lines are crossed at their inner ends, and within these ends next to the center star are inverted fan-shaped figures 4. Next to the circular or encircling line are fan-shaped figures 5, and outside the circular or encircling line are fan-shaped figures 6. Between the ends next to the center star are cross figures 7, having hatching 8 on the arms thereof. Next to the circular or encircling line are figures 9, having radial lines, and between the outside fan-shaped figures are lattice figures 10.

Having thus described my invention, the following is what I claim as new therein and desire to secure by Letters Patent:

The design for the ornamentation of glass and other ware, substantially as herein shown and described.

THOMAS G. HAWKES.
